(57) **CLAIM**

The ornamental design for a cocktail shaker, as shown and described.

DESCRIPTION

FIG. 1 is a top-side perspective view of a cocktail shaker, showing the new design;

FIG. 2 is a bottom-side perspective view thereof;

FIG. 3 is a front view thereof, the back view being a mirror image thereof; and,

FIG. 4 is a top view thereof.

The broken lines in the drawings depict portions of the cocktail shaker that form no part of the claimed design.
